COMBINATION VISE AND CLAMP

William Mark Dennis, 1901 Stone St., Falls City, Nebr.
Filed June 12, 1959, Ser. No. 820,066

3 Claims. (Cl. 269—9)

This invention relates to tools and more particularly to a combination vise and clamp which may be utilized for a wide variety of operations.

The combination vise and clamp of this invention may be permanently mounted on a bench or other support to be utilized for the normal functions of a vise and also in this position may be utilized as a clamp for securing parts together under pressure and which is so designed as to accommodate a wide range of sizes. The tool of this invention may also be utilized as a portable tool, that is the same need not be secured to a support and the tool may be utilized in this condition as a clamp for various objects of a wide range of sizes and furthermore, the tool may be utilized for wire stretching or similar functions which serve to provide a very versatile tool having a wide variety of uses.

It is accordingly an object of the invention to provide a combination vise and clamp which may be permanently installed on a suitable support or utilized as a portable tool to perform a wide variety of clamping functions accommodating a wide variety of sizes and which may be also utilized in the manner of a conventional vise.

A further object of the invention is the provision of a combination vise and clamp which may be conveniently adapted for use in wire stretching or similar operations and is particularly adapted for use in stretching fence wires.

A still further object of the invention is the provision of a combination vise and clamp which may be conveniently and economically manufactured from readily available light-weight materials and which may be of a size and shape to require a minimum of space and at the same time, provide adequate strength and clamping power, as well as wide utility.

Further objects and advantages of the invention will be apparent from the following description taken in conjunction with the accompanying drawing wherein:

FIG. 1 is a top plan view of a combination vise and clamp constructed in accordance with this invention;

FIG. 2 a side elevational view of the vise shown in FIG. 1 with parts broken away for greater clarity and showing in dotted outline an object clamped between jaws of the tool when using the same in the manner of a conventional vise;

FIG. 3 a side elevational view of the combination vise and clamp and showing an elongated extension member mounted thereon for accommodating an abutment, which abutment cooperates with a movable jaw to clamp an object shown in dotted outline, the abutment also being adjustable on the extension member; and

FIG. 4 a fragmentary side elevational view showing the manner of adapting the tool of this invention for use in stretching wire and further showing in dotted outline a post, together with a post-engaging foot mounted on the tool.

With continued reference to the drawing and particularly FIGS. 1 and 2, there is shown a combination vise and clamp constructed in accordance with this invention, together with the use of the same as a vise and in which the tool may well comprise spaced parallel side bars 10 and 11 formed of angle iron and providing a base for the tool and if desired, the side bars 10 and 11 may be provided with apertures 12 for receiving suitable fastening means to secure the tool to a suitable support. An end plate 13 may be fixed to one end of the side bars 10 and

2

11 by welding or any other suitable means and the end plate 13 projects laterally above the side bars 10 and 11 as shown in FIG. 2, and may, if desired, be provided with a base plate 14 to provide a fixed jaw. A second end plate 15 is fixed to the opposite ends of the side bars 10 and 11 by welding or any other suitable means and it is to be noted from an inspection of FIG. 2, that the end plate 15 terminates at the upper edge in alignment with the upper edges of the flanges 16 and 17 of the side bars 10 and 11.

A screw threaded shaft 18 is disposed between the flanges 16 and 17 of the side bars 10 and 11 and is rotatably mounted in the end plates 13 and 15. The shaft 18 extends through the end plate 13 and the outwardly projecting end 19 of the shaft 18 serves to receive an actuating means in the form of a bar or crank 20 and the actuating means 20 may be adjusted to provide variable leverage and may be secured in adjusted position by a set screw 21 threadedly received in the projecting end 19 of the screw threaded shaft 18. If desired, however, the set screw 21 may be dispensed with and the actuating means 20 merely slidably in an aperture in the projecting end 19 of the shaft 18 in a manner which is conventional in vise structures. Also the projecting end 19 of the shaft 18 may, if desired, be provided with other types of actuating means, such as a wrench receiving portion, not shown.

A movable jaw 22 is slidably mounted between the flanges 16 and 17 of the side bars 10 and 11 and the jaw 22 is provided with a downwardly projecting portion 23 having a threaded aperture 24 therein which provides a nut threadedly engaging the threaded shaft 18. The movable jaw 22 is provided with a plate 25 serving to provide a jaw face opposite the jaw face on the plate 14 of the end plate 13 and in the use of the tool as a vise as shown in FIG. 2 in dotted outline, an object 26 may be engaged between the plates 14 and 25 and tightly clamped therebetween by operation of the screw threaded shaft 18 to move the jaw 22 toward the end plate 13.

The end plate 15 may be provided with an extension mounting means in the form of a projection 27 having an aperture 28 in the outer end thereof and if desired, the aperture 28 may be screw threaded to removably receive the screw threaded end of an elongated extension member 29. If desired, however, the screw threads 28 may be dispensed with and the elongated extension member 29 merely positioned in the aperture in the mounting means 27 or secured thereto in any other desired manner. The extension member 29 may be a pipe or other suitable tubular member of any desired length and serves to adapt the tool for accommodating objects of a wide variety of sizes.

Slidably mounted on the elongated extension member 29 is an abutment 30 which may be adjustably secured on the extension member 29 by a set screw 31 or other suitable means and the abutment 30 may be provided with a jaw face 32 which is positioned opposite a jaw face 33 provided on the movable jaw 22.

When it is desired to utilize the tool of this invention as a clamp, it is only necessary to provide an elongated extension member 29 of the desired length and to position the abutment 30 thereon at the desired location, whereupon an object to be clamped as shown at 34 in dotted outline in FIG. 3, may be positioned between the jaw face 32 on the abutment 30 and the jaw face 33 on the movable 22 and upon operation of the threaded shaft 18, the jaw 22 moves toward the abutment 30 to clamp the object 34 therebetween. This operation may be performed with the tool secured to a bench or other support or the tool may be utilized as a portable device and applied to the work to be clamped.

The tool of this invention may also be utilized to stretch wire, such as is utilized in erecting fences and as shown in FIG. 4, in order to adapt the tool for this operation, it is only necessary to substitute a suitable post engaging or other foot 35 for the abutment 30 on the elongated extension member 29 and the foot 35 would normally be positioned on the outer end of the extension member 29 and would engage a post or other abutment as shown in dotted outline at 36 in FIG. 4. A conventional wire gripping means 37 may be secured in any desired manner as by a screw threaded stud 38 to the movable jaw 22 and as clearly shown in FIG. 4, the gripping means 37 serves to engage and grip a wire 39 and upon operation of the screw threaded shaft 18 to move the movable jaw 22 in the direction of the arrow as shown in FIG. 4, the wire 39 will be stretched and the reaction force will be applied to the post 36 through the post-engaging foot 35.

It will be seen that by the above described invention, there has been provided a very simple, yet highly versatile combination vise and clamp which upon operation and movement of the movable jaw 22 in the direction of the arrow shown in FIG. 2, serves to operate as a vise and upon movement of the movable jaw 22 in the direction of the arrow as shown in FIG. 3 and in cooperation with the abutment 30 on the extension member 29 serves to operate as a clamp. Since the tool is also capable of wire stretching operations as shown in FIG. 4, obviously, the single tool of this invention is capable of a wide variety of operations and provides a tool highly useful in the home workshop or in commercial establishments. The tool may be constructed of suitable lightweight alloys which provide adequate strength combined with light weight and in view of the provision of the extension member which may be of any desired length, the range of sizes accommodated by the tool is substantially infinite.

It will be obvious to those skilled in the art that various changes may be made in the invention without departing from the spirit and scope thereof and therefore the invention is not limited by that which is shown in the drawing and described in the specification, but only as indicated in the appended claims.

What is claimed is:

1. A combination tool comprising spaced parallel side bars formed of angle irons and providing a base for said tool, an end plate fixed to one end of said side bars and projecting laterally therefrom at substantially right angles

to provide a fixed jaw, a second end plate fixed to the opposite end of said side bars, a screw threaded shaft rotatably mounted in said end plates and disposed between said side bars, one end of said shaft projecting outwardly of said first end plate, an actuating means on the projecting end of said shaft, a movable jaw slidably mounted on said side bars and having a nut threadedly engaging said shaft, a jaw face on said movable jaw opposite said fixed jaw, an extension mounting means fixed to said second end plate in alignment with said shaft, a separate elongated extension member removably received in said extension mounting means and projecting outwardly of said second end plate, an abutment carried by said member outwardly of said second end plate and work engaging means on said movable jaw cooperating with said abutment.

2. A combination tool as defined in claim 1, in which said abutment is adjustably received on said member and is provided with a second jaw face, and in which said work engaging means comprises a third jaw face on said movable jaw opposing said second jaw face.

3. A combination tool as defined in claim 1 in which said abutment comprises a post engaging foot, and in which said work engaging means comprises a wire gripping clamp.
